REVERSIBLE STOVE CONSTRUCTION

Lewis Moore, Joliet, Ill., assignor to The Moore Corporation, Joliet, Ill., a corporation of Illinois

Original application April 13, 1933, Serial No. 665,941. Divided and this application March 23, 1934, Serial No. 717,036

4 Claims. (Cl. 126—214)

This invention relates in general to stoves, and has more particular reference to stove top covers of simple construction, which may be raised and lowered into and out of position with ease of operation. This application is a division of my application Serial No. 665,941, filed April 13, 1933.

An important object of the invention is the provision of a stove top cover which is insulated against heat when the table top is lowered after the burners have been used.

A further important object of the invention is the provision of a stove top cover which may easily be raised or lowered without requiring the moving or adjusting of other parts.

Another important object of the invention is the provision of a stove table top which automatically assumes an upright position, when raised, and remains in such position without the use of fastening means.

Numerous other objects and advantages of the invention will be apparent as it is better understood from the following description, which, when taken in connection with the accompanying drawings, discloses a preferred embodiment thereof.

Referring to the drawings,

Figure 1 is a front elevation of a stove embodying my present invention;

Fig. 2 is a transverse vertical section through the top of the burner box unit of a stove embodying my invention;

Fig. 3 is a rear elevation of the burner with the top in closed position;

Fig. 4 is a fragmentary rear elevation with the top shown in raised position;

Fig. 5 is a section taken substantially on the line 5—5 of Fig. 3; and

Fig. 6 is a section similar to Fig. 5 and showing the top in raised position.

For the purpose of illustrating my invention I have shown on the drawings a stove construction generally, comprising a frame 15, a combined oven and broiler unit 16, and a burner box unit 17. Four legs 18, of suitable form and construction, are provided at their tops with flat parts arranged at right angles and adapted to receive four angle iron rails which may be bolted in place. These angle iron rails are arranged so that the apex or corners of the angles are adjacent and with an opening through the stove.

As more particularly described in my co-pending application, of which this is a division, the combined oven and broiler unit 16 and burner box unit 17 are so constructed that they fit within the bottom frame thus provided and rest upon

the tops of the side and end rails. The burner box unit, to which the instant invention more particularly relates, is a completely enclosed integral unit and contains a drawer 19 mounted below a burner containing section, indicated at 21. 5

As will be apparent from the drawings, the burner box unit comprises an integral unit and consists of a bottom plate of pressed sheet metal, side walls, a back wall 22, a top rectangular frame 23 of angle iron construction, and a front cast 10 rectangular frame 24. These parts are so constructed and arranged as to greatly facilitate assembly and to produce a rigid, substantial structure of relatively light gauge material.

The top frame consists of four angle irons 15 welded together at their ends, the two side angle irons extending across the ends of the front and back angle irons. The horizontal flanges of all four angle irons are at the top, and those of the side angle irons extend outwardly and those of the front and back angle irons extend forwardly. 20

Viewing Fig. 2, the front cast frame 24 is provided with an inset top flange 25 at the opening. Bolts 26 are arranged to extend rearwardly from the top of the frame 24 through openings in 25 the front angle iron of the top frame.

The back wall 22 consists of a single flat sheet of metal secured at 27 to the rear face of the rear angle member of the top frame and to the inner face of the rear upturned flange of 30 the bottom plate.

As shown in Fig. 2, the burner box unit is provided with a cast iron stove top 28 and a skeleton vessel supporting grate 29 of usual or preferred construction. A front wall of the 35 burner compartment 31 is provided to fit within and suitably secured to the top part of the front cast iron frame 24 of the stove. A manifold 32 for the burners is arranged within this unit and back of the wall 31. It enters the unit 40 through an opening at the rear and is disposed along one side wall and across the front of the unit. It is held in position from the front cast frame and to this end clamping members or 45 arms 33 are cast integral with the frame and cooperate with companion clamping members 34 to hold the manifold in position. Burner valves 35 are arranged to extend up from the manifold and have gas outlets 36 adapted to be arranged in the mixing chambers 37 of burners 38. These 50 burners are supported at the front upon the gas outlets 36 and at the rear upon brackets 39 of angle form which extend down from a fastening means 41 from the top angle iron 23 along the front of the back wall and thence forwardly be- 55

neath the burner as may be observed in Fig. 2. Openings 42 are provided in the wall 31 to permit the passage of valve control means 43.

A fixed sheet metal apron 44 extends up from 5 and is spaced above the top plane of the burner box unit 17 and is rigidly secured thereto. This apron extends longitudinally of the burner box unit or stove and is provided at its ends with flanges 45 extending rearwardly to allow of its 10 being rigidly secured by vertical brackets or posts 46 spaced slightly away from the side edges of the apron, as shown in Figs. 3 and 4. These posts 46 are secured at their lower ends to the burner box 15 as indicated at 47 by bolts 48 or other suitable fastening means. Adjacent the top and bottom of its flanged edges, the apron is secured to the vertical supporting posts at 49 by bolts or other suitable fastening means. As shown in Figs. 5 and 6, the apron with its supporting 20 brackets or posts is spaced rearwardly from the vertical plane of the back wall 22 of the burner box unit, for a purpose which will later be described.

A table top stove cover, generally indicated 25 at 51, is provided for the burner box unit and is or may be provided with a handle 52 to facilitate raising and lowering. This top is hinged at 53 along the rear of the stove and preferably consists of two metal sheets, the topmost one of 30 which is flanged downwardly at 54 at the front of the stove, and thence inwardly at 55 to provide a box-like edge. The inwardly extending portion 55 rests upon a projection 56 of any suitable material secured either to the stove top 35 or to the cover.

The top plate of the table top extends rearwardly through an opening or slot 57 provided between the top of the back wall 22, extension 58, and the lower edge of apron 44. This extension 40 58, extending longitudinally of the rear wall of the stove, is secured to the back 22 at 27 and forms a part of the hinge 53. The rearward extension of the plate 51 is bent upwardly and thence rearwardly at 59 to receive an arm 61 to 45 which one end of a counterbalancing spring 62 is connected. The other end 62 of the spring is fastened to the back of the stove at 63 as may be observed in Fig. 3 and two such springs are provided.

50 The lower sheet of the table top of the stove, indicated by reference character 64, is flanged at its front end, then extended forwardly until it contacts the inwardly extending portion 55 of the top sheet of the table top where it is bent 55 so as to overlie and rest upon the inwardly extending portion 55 where it is spot welded or otherwise suitably secured. At its rear end it is flanged downwardly at 65, then rearwardly and upwardly, as indicated at 66, and against the 60 back extension 58. This construction creates a box-like structure 67 which provides an air space within the table top to insulate its upper surface from the heat of the burners when the top is lowered after the burners have been in service. 65 If desired, this space may be filled with insulating material of any desired character.

70 It will be apparent from the foregoing description that the table top or cover may be readily raised or lowered without affecting the relative position of the other parts of the stove. When the top 51 is raised that portion of the top plate which extends rearwardly of back wall extension 58 rests against this extension and the

cover portion itself rests against the apron 44. as shown in Fig. 6.

It will be manifest that when the table top is raised the counterbalancing spring will serve to securely support and maintain it in upright position, and that because of the novel construction of the parts, very little effort is needed to lower the top to closed position. When the top is closed down over the burners its weight will be sufficient to overcome the tension of the counterbalancing spring. 10

It is thought that the invention and many of its attendant advantages will be understood from the foregoing description, and it will be apparent that various changes may be made in the form, 15 construction and arrangement of the parts without departing from the spirit and scope of the invention or sacrificing all of its material advantages, the form hereinbefore described being merely a preferred embodiment thereof. 20

I claim:

1. A range, comprising a body having a burner top, an apron extending up from the body, a lid member hinged to a portion of said body adjacent said burner top and adapted to close 25 down over said burner top and composed of metal sheets bent to provide an inclosed box structure, one of said sheets extending horizontally between said apron and said body when said lid is closed, and spring means counterbalancing the weight 30 of said lid.

2. A range, comprising a body having a burner top, an apron extending up from the body, a lid member hinged to a portion of said body adjacent said burner top and adapted to close 35 down over said burner top, said lid member being composed of double walls spaced apart for insulation, one of said walls being adapted to extend rearwardly of said body and between said body and said apron when said lid is closed, and 40 resilient means secured to said rearwardly extending wall and said body to counterbalance the weight of said lid.

3. A range, comprising a body having a burner top, an apron extending up and spaced apart 45 from said body, a lid member hinged to a portion of said body adjacent said burner top and adapted to close down over said burner top said lid member comprising upper and lower walls spaced apart for insulation, said upper wall extending rearwardly of and between said body and said apron when said lid is closed, and spring means secured at one end to the extension of said upper wall and at the other end to said body to maintain said lid member in open position. 50

4. A range, comprising a body having a burner top, said body comprising front, back, and side walls, top and bottom, an apron secured to said back wall and spaced back of the vertical plane thereof and extending up and spaced above the horizontal plane of the top, a lid member hinged to a portion of said body adjacent said burner top and adapted to close down over said burner top and adapted when open to rest in front of said apron, said lid member comprising upper and lower metal sheets spaced apart for insulation, said upper sheet having a portion adapted to extend rearwardly of and between said top and apron when said lid is closed, and spring means secured to said upper sheet extension and the back wall to counterbalance the weight of said lid member. 65

LEWIS MOORE.
